UNITED STATES PATENT OFFICE.

JOHN D. DUNN, OF LOS ANGELES, CALIFORNIA.

GOLF OR OTHER CLUB.

SPECIFICATION forming part of Letters Patent No. 726,885, dated May 5, 1903.

Application filed January 24, 1902. Serial No. 91,019. (No model.)

To all whom it may concern:

Be it known that I, JOHN D. DUNN, a subject of the King of Great Britain, residing at Los Angeles, in the county of Los Angeles and State of California, have invented certain new and useful Improvements in Golf or other Clubs, of which the following is a specification.

My invention relates to golf or other clubs, and has for its object to provide such a club with a resilient driving-face by which the ball may be driven farther and with less effort than by means of the clubs now in use.

It consists, essentially, of such a club having a resilient face and the novel features more particularly pointed out in the claims.

Referring to the accompanying drawings, Figure 1 shows the block or central part of the core and the preferred method of covering the same. Fig. 2 shows the completed core, and Fig. 3 the core in position in the driving-face.

The block A is made of any suitable material, preferably of medium hardness and some resiliency, as gutta-percha, and of suitable shape. It is then covered by being overwound with strands of soft elastic rubber.

The rubber strands may be wound in one direction only or in both and may be stretched to any desired tension. The core being completed, it is secured in position in the driving-face in any convenient manner, preferably by molding gutta-percha around it. This method secures a closer contact with the core, and consequently produces greater resiliency. The face is then secured to the club, the whole forming a club of great driving power by reason of the increased weight and resiliency of the face.

Having now fully described my invention, what I claim is—

1. In a golf or other club, a driving-face having a resilient core consisting of a block overwound with strands of elastic material, as set forth.

2. In a golf or other club, a driving-face having a resilient core consisting of a gutta-percha block overwound with strands of rubber, as set forth.

JNO. D. DUNN.
